US0D1083839S

(12) **United States Design Patent** (10) **Patent No.:** **US D1,083,839 S**
(45) **Date of Patent:** **** Jul. 15, 2025**

(54) **MULTIFUNCTIONAL CHARGING CABLE WITH HUB**

(71) Applicant: **Ningbo Gecen Promotion & Gift Co., Ltd.**, Zhejiang (CN)

(72) Inventor: **Weijin Ying**, Zhejiang (CN)

(**) Term: **15 Years**

(21) Appl. No.: **29/921,769**

(22) Filed: **Dec. 19, 2023**

(51) LOC (15) Cl. **13-03**

(52) U.S. Cl.

USPC **D13/153**

(58) **Field of Classification Search**

USPC D13/153, 133, 154, 147, 433

CPC .. H01R 13/03; H01R 13/7175; H01R 13/514;

H01Q 1/46

(57) **CLAIM**

The ornamental design for a multifunctional charging cable with hub, as shown and described.

DESCRIPTION

FIG. 1 is a first perspective view of a multifunctional charging cable with hub showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is another perspective view thereof.

The broken lines in the drawings depict portions of the multifunctional charging cable with hub that form no part of the claimed design.

1 Claim, 8 Drawing Sheets
